DESIGN FOR A HEATER

William L. Sharpe, Steubenville, Ohio, assignor to The Ohio Foundry & Manufacturing Company, Steubenville, Ohio, a corporation of Ohio

Application July 20, 1934, Serial No. 52,648

Term of patent 3½ years

To all whom it may concern:

Be it known that I, WILLIAM L. SHARPE, a citizen of the United States, residing at Steubenville, in the county of Jefferson, State of Ohio, have invented a new, original, and ornamental Design for a Heater, of which the following is a specification, reference being had to the accompanying drawing, forming a part thereof.

Fig. 1 is a face view of a heater embodying my new design, and Fig. 2 is a side view thereof.

I claim:

The ornamental design for a heater, as shown.

WILLIAM L. SHARPE.
